UNITED STATES PATENT OFFICE.

HARRY M. EDWARDS, OF BROOKLYN, NEW YORK, ASSIGNOR TO WILLIAM VOGEL & BROTHERS, OF SAME PLACE.

LIGHTING IMPLEMENT.

SPECIFICATION forming part of Letters Patent No. 604,693, dated May 24, 1898.

Application filed August 24, 1897. Serial No. 649,374. (No model.)

To all whom it may concern:

Be it known that I, HARRY M. EDWARDS, a citizen of the United States, residing at Brooklyn, in the county of Kings and State of New York, have invented certain new and useful Improvements in Lighting Implements; and I do hereby declare the following to be a full, clear, and exact description of the invention, such as will enable others skilled in the art to 5 which it appertains to make and use the same.

My invention relates to that class of devices known as "lighting implements," in which two rods or tubes are employed connected to a handle and one provided with a key with 10 which to turn on the gas and the other forming a receptacle for holding a taper to ignite the gas or lamp. These devices as heretofore constructed have been provided with spring jaws or points or similar devices to engage 15 the end of the taper with the thumb-piece, all of which have been found objectionable, as the constant action of pushing the taper out for lighting and drawing it within the tube to extinguish it soon frays out the end 20 and causes it to become detached from the thumb-piece, and consequently rendering it necessary to force the taper out of the tube, remove the frayed end, and reconnect the taper with said thumb-piece.

30 The object of my invention is to overcome the difficulties heretofore experienced in this particular and to produce a device that when the taper is once connected will be firmly held and which shall be strong and durable.

35 The invention consists in a novel construction of taper-holder for connecting the taper with the thumb-piece, whereby the taper is firmly connected thereto and all liability of the taper becoming detached is avoided, all as 40 hereinafter explained.

In the accompanying drawings, Figure 1 is an enlarged side elevation of the upper end of the implement, showing the rod or tube provided with a key for turning on the gas and

45 the curved tube for containing the taper with one form of my improved holder. Fig. 2 is a similar view showing a modification of the holder. Fig. 3 is an enlarged view of the

holder shown in Fig. 1. Fig. 4 is an enlarged view of the holder shown in Fig. 2.

50

The tubes A A' may be of any usual or desired construction, one of which has affixed thereto the key-piece a, by which to turn on the gas, and the other forming the taper-holder. The tubes are connected together in 55 any desired manner and are fixed to a suitable handle B, the tube for holding the taper being curved outward away from the key-tube in the usual manner.

The device by which the taper is moved in 60 and out for lighting and extinguishing consists of the thumb-piece C, made in any desired form, having the flattened portion C' to slide in the groove D, and to this flattened portion is connected the loop or perforated 65 extension E, or said extension may be formed integral with the flattened portion, as shall be found most desirable. This extension, as above stated, consists either of the loop or eye e, formed by bending the forward end 70 backward, as shown in Figs. 1 and 3, or may be formed by perforating the extension, as shown in Figs. 2 and 4, or in any other preferred manner, whereby to form an eye or closed loop around or through which the taper 75 may be looped or passed and permits said taper to be bent back upon itself or forming a loop in said taper. When the taper is thus connected and drawn within the tube, the taper will be engaged and firmly clamped by the 80 wall of said tube in a manner that will be readily understood and appreciated.

Having now described my invention, what I claim as new, and desire to secure by Letters Patent, is—

85

In a lighting implement, a taper-holder tube, in combination with a thumb-piece provided with an extension made in closed-loop or eye form, through which the taper is adapted to be hooked substantially described.

90

In testimony whereof I affix my signature in presence of two witnesses.

HARRY M. EDWARDS.
